UNITED STATES PATENT OFFICE

91,918

DESIGN FOR A LENS STRAP

Samuel E. Bouchard, Rochester, N. Y., assignor
to Bausch & Lomb Optical Company, Rochester,
N. Y., a corporation of New York

Application February 16, 1934, Serial No. 50,750

Term of patent 7 years

To all whom it may concern:

Be it known that I, SAMUEL E. BOUCHARD, a citizen of the United States and a resident of Rochester, county of Monroe and State of New York, have invented a new, original, and ornamental Design for a Lens Strap, of which the following is a specification, reference being had to the accompanying drawing, forming a part hereof.

The figure is a perspective view of a lens strap embodying my new design.

I claim:

The ornamental design for a lens strap substantially as shown.

SAMUEL E. BOUCHARD.
